UNITED STATES PATENT OFFICE.

WILLIAM D. GRAY, OF MILWAUKEE, WISCONSIN.

TEST-PLATE FOR ROLLER-MILLS.

SPECIFICATION forming part of Letters Patent No. 273,065, dated February 27, 1883.

Application filed September 19, 1882. (No model.)

To all whom it may concern:

Be it known that I, WILLIAM D. GRAY, of Milwaukee, in the county of Milwaukee and State of Wisconsin, have invented certain Improvements in Test-Plates for Roller-Mills, of which the following is a specification.

This invention relates to a device intended to facilitate and determine the accurate relative adjustment of the companion rolls employed in roller grinding-mills in such manner as to bring the axes of said rolls to a common plane, the device being more particularly designed for use in connection with those rolls which have porcelain surfaces.

My device consists essentially of a plate or frame, preferably cast complete in one piece, adapted to extend from end to end above the rolls, and provided at its two ends with depending flanges or feet adapted to extend downward past the ends of the rolls and rest upon the journals or shafts thereof, the lower surfaces of the feet or flanges being all in one and the same plane. The plate thus constructed may be applied above and across the two grinding-rolls of a mill and sustained by its depending flanges upon the journals without coming in contact with the grinding-surfaces of the rolls. The journals of the rolls being made of equal size, as usual, the plate will rest firmly thereon whenever the two rolls are adjusted with their axes in one and the same plane; but if there be the slightest deviation from said plane the plate will be free to rock or tip upon the journals. It will thus be seen that the operator, in order to insure the proper adjustment of the rolls, has only to place the plate upon their journals, and then adjust the rolls until the plate receives a firm and rigid support, which fact is in itself a positive proof that the rolls are in the required position.

The present device differs from the test-plate for which Letters Patent of the United States have been already granted to me, in that the present plate has the downwardly-extending ends adapted to rest upon the journals of the rolls without touching the surface, while in the former device the plate came into direct contact with said surface, and was supported thereby.

The present device is peculiarly advanta-

geous when used in connection with porcelain rolls and other rolls having mineral surfaces, which are liable on the one hand to be injured by contact with the plate, and on the other to deface the surface of said plate; also, for use upon rolls which are corrugated or ribbed spirally, and which will not always give a firm support to the plate described in my former patent, even when their axes are arranged in line.

Referring to the accompanying drawings, Figure 1 represents a top plan view of my present device in its preferred form; Fig. 2, a sectional elevation of the same in an operative position on the line *x x*, Fig. 1; Fig. 3, a sectional elevation of the same in an operative position on the line *y y*, Fig. 1.

A represent the bodies of the grinding-rolls, and B B their journals or shafts.

C represents my test-plate, consisting of a rectangular plate or body, *a*, having at its two ends depending flanges or feet *b*, the lower surfaces of which are planed or ground accurately to one and the same plane.

The plate is made of such length and the flanges of such height as regards the size of the rolls upon which it is to be used that it may be placed in position over and across the rolls, as represented in Fig. 3, with the feet *b* resting upon the journals of the rolls and sustaining the body *a* above their grinding-surfaces.

In order to prevent the plate from bending, it is preferred to construct longitudinal flanges *c* on its edges. The plate is also lightened, and a view between the rolls permitted, while the plate is thereon, by forming a central opening, *d*, in the body of the plate, as shown. For the sake of convenience in handling the plate, I ordinarily provide the same at the two ends with projecting handles *e*.

It is manifest that the form of the plate may be modified as desired, provided only that it is adapted to extend from end to end of the rolls, and provided with supporting feet or flanges adapted to rest upon the journals of the rolls and sustain said body, the essential requirement being that the device shall be of such character as to rest solidly upon all four journals when the axes of the two rolls coincide, but at no other time.

Having thus described my invention, what I claim is—

1. The improved test-plate for roller-mills, consisting of a body portion, *a*, adapted to extend from end to end above both rolls, and provided with depending flanges or feet adapted to rest in one and the same plane upon the journal of the respective rolls.

2. A test-plate for roller-mills, having at its ends depending feet or flanges adapted to rest upon the journals of two rolls, and to sustain the body portion of the plate above and

out of contact with the grinding-surface of said rolls, substantially as described and shown.

3. The improved test-plate for roller-mills, having the body portion, the depending flanges or feet, adapted, as described, to extend downward past the ends of the rolls, and the handles *c*, whereby the plate may be adjusted in position.

WILLIAM DICKSEN GRAY.
